(57) CLAIM

The ornamental design for hockey game table goal, as shown and described.

DESCRIPTION

FIG. 1 is a right, front perspective view of a hockey game table goal showing our new design;

FIG. 2 is a top plan view thereof;

FIG. 3 is a front view thereof;

FIG. 4 is a right side view thereof, the left side being symmetrical; and,

FIG. 5 is a rear elevational view thereof.

FIG. 6 is a perspective view thereof, shown the design in its environmental use;

FIG. 7 is a top plan view of FIG. 6;

FIG. 8 is a right side view of FIG. 6, the left side being symmetrical; and,

FIG. 9 is a rear view of FIG. 6.

The broken lines of table, shown in FIGS. 6-9 are for illustrative purpose only and form no part of the claimed design.
